SEAMING MACHINE

Willy Diezel, Bridgeport, Conn., assignor to The
Max Ams Machine Company, Bridgeport,
Conn., a corporation of New York

Application January 16, 1942, Serial No. 426,967

2 Claims. (Cl. 113—24)

The present invention relates generally to seaming machines, and more specifically to the so-called closing machines that act to seam a can-end or cover to a filled can-body.

The main object and feature of the invention is to provide means for feeding and bringing the can-body to rest on the platform at the seaming station of the machine in such a way that the tendency to spill the contents of said can-body is minimized so that the machine can be run at a high speed without unduly disturbing said contents.

Fig. 1 is a vertical sectional view of a seaming machine, the section being substantially on the plane of line 1—1 of Fig. 2;

Fig. 2 is a horizontal sectional view substantially on the plane of line 2—2 of Fig. 1;

Fig. 3 is a view in elevation looking in the direction of arrow 3 of Fig. 2, with parts broken away and in section;

Fig. 4 is a more or less diagrammatic plan view of the cover feeding and marking device;

Fig. 5 is a vertical sectional view substantially on the plane of line 5—5 of Fig. 2;

Fig. 6 is a vertical sectional view substantially on the plane of line 6—6 of Fig. 2;

Fig. 7 is a vertical sectional view substantially on the plane of line 7—7 of Fig. 2;

Figs. 8 to 11 are fragmentary views showing the steps involved in transferring the can-body from the can-body conveyor to the pedestal and in freeing said can-body from the control of the can-body conveyor.

Fig. 12 is a diagrammatic view showing the relative travel of the can and the turret; and

Fig. 13 is a diagrammatic development view of the cam for actuating the turret.

1 indicates a platform located at the seaming station of the machine and having means for raising and lowering said platform, consisting here of cam 2 and lever 3 pivoted at 4 and pivotally connected to said platform at 5. The function of this platform is to raise a can-body and a cover into engagement with the seaming mechanism, indicated generally at 6, which seaming mechanism may be of any suitable construction and need not be described in detail. 7 is a turret, intermittently rotatable step by step by means that will be described at a later point. This turret has four pockets 8, each to receive a cover and a can-body. 9 is a can-body support that extends in a straight line to pedestal 1, and 10 indicates a conveyor having pins as 11, extending up through a slot 9a in said support, for pushing can-body 12 over said support and to uninter-

ruptedly transfer said can-body from said support to said pedestal while the latter is in its lower position. Conveyor 10 is trained over sprockets 13 and 14 and it will be seen that said conveyor has unobstructed passage through an opening 15 in the pedestal. The speed of conveyor 10 is uniform and can-body 12, therefore, is not subject to any change in speed in passing from can-support 9 to pedestal 1. It must be emphasized that turret 7 does not transfer can-body 12 from can-support 9 to the pedestal, but only acts thereafter to free it from the propelling action of pin 11, to position or center the can-body with respect to said pedestal, and to bring it to a state of rest. How this is accomplished will be understood from a consideration of Figs. 1, 3 and 7 to 13. Turret 7 is mounted on a rotatable shaft 16 that is intermittently turned 90° by a suitable variable speed mechanism. In the present instance, such speed mechanism consists of cam 17, mounted on shaft 18, with which cam engage four rollers 19, mounted on a disk 20, carried by shaft 16. A development of cam 17 is shown in Fig. 13, from which it will be understood that, while a cam 25 roller 19 is being acted upon by that active portion of the cam which extends from 17a to 17b, said shaft 16 is brought from a state of rest and begins its turning movement at a rapidly accelerated speed. Furthermore, that when that active portion of cam 17 that lies between 17b and 17c acts upon a roller 19, the speed of shaft 16 will be substantially constant and will be substantially equal to that of conveyor 10 which is feeding the can-body. Again, while that active portion of cam 17 that lies between 17c and 17d acts upon a roller 19, the speed of shaft 16 is slightly accelerated. Finally, when that active portion of cam 17 that lies between 17d and 17e acts upon a roller 19, the speed of shaft 16 is decelerated and brought to a state of rest. When a roller 19 is engaging the straight or inactive portions 17f and 17g of said cam 17, shaft 16 and turret 7 stand still and the seaming operation takes place.

45 The action of cam 17 is similar to that of a Geneva stop motion in that it imparts an intermittent movement to the turret, but this movement is, as above pointed out, a variable one and how this is accomplished will now be described. At the end of the seaming operation the cam roll marked 19a in Fig. 2 will be at the point marked 17a in Fig. 13 and the continued rotation of the cam now causes said roll 19a to enter the active portion of the cam and eventually to swing out 50 of engagement with said cam at the point 17h.

This occurs at a time when the turret is half way through its uniform motion between points 17b and 17c. But when roll 19a swings out of engagement with the cam at the point 17h, another roll, marked 19b (in Fig. 2), is entering the cam at the point 17k (in Fig. 13) and the uniform motion of the turret continues until said roll 19b arrives at point 17c when the motion of the turret is accelerated. Cam roll 19b then completes the turning movement of the turret and then enters inactive cam portion 17g. Considering, therefore, the action of one cam roll, it will be seen that it enters cam 17 at the point 17k, during one intermittent step of the turret, and leaves it at 17h, during the next intermittent step of said turret, and that a single step of the turret is effected partly by one cam roll and partly by another cam roll.

Considering now the plotting of the movements of turret 1 indicated in Fig. 12, it will be seen that line 1a indicates the center line of a pocket 8 at the beginning of the turning movement of the turret. This turning movement, as has been explained, is at a rapidly accelerated speed until the center line of such pocket 8 is at the point 1b. At the beginning of the turning movement of the turret from the position 1a, a can-body 12 will occupy the position indicated at 12a in Fig. 12 and, as the can-body is traveling in a straight line toward the pedestal at a constant speed, it is necessary to get the leading wing 8a of pocket 8 out of the way of said can-body and therefore the turret is given the accelerated speed indicated between points 1a and 1b. To prevent pocket 8 from engaging the can-body prematurely and in order to allow conveyor 10 and pin 11 to uninterruptedly feed the can-body to pedestal 1, the speed of the turret is then rendered substantially uniform between lines 1b and 1c and substantially equal to that of the speed of conveyor 10 and pin 11. The can-body having been placed partially upon pedestal 1 by pin 11 (Fig. 8), the speed of the turret is slightly accelerated to thereby bring pocket 8 of the turret in contact with the can-body and to advance it a trifle ahead of pin 11 (Fig. 9). This action begins at the point 1c. Shortly thereafter, platform 1 starts to rise (Fig. 10) and the slight acceleration of the speed of the turret and the rise of pedestal 1 above the plane of pin 11 frees the can-body from control of and contact with pin 11 and places its movement entirely in control of turret 1. The speed of the turret now decelerates from point 1d until the point 1e is reached when the can-body is central of pedestal 1 and is there brought to a standstill (Fig. 11). The advantage of this construction is that the can-body is freed from the control of pin 11 while said pin is traveling in a straight line and therefore a much smaller amount of acceleration of the turret is needed and consequently no sudden jar is imparted to the can-body. For it will be understood that, if the turret were used to transfer the can-body from can-support 9 to pedestal 1, then sprocket 14 would have to be located in front of said pedestal and pin 11 would therefore be traveling, at the moment of transfer, over a curved surface (the sprocket), which curved surface would incline pin 11 from the vertical and therefore tend to push the can-body ahead of the speed imparted to it during the vertical position of pin 11. Consequently, under such conditions, the turret would have to be speeded up to a much greater extent and that would increase the speed of the can-body rather suddenly.

Associated with can-support 9 and with the pedestal are guides 21 and 22 and it will be understood that, after the cover has been seamed to the can-body and the next movement of turret 7 occurs, the finished body and cover will be moved out of the machine by the movement of the turret.

23 indicates a cover feeding device intended to feed the covers singly to a marking device 24 and thereafter to one of the pockets 8 of turret 7, said pocket receiving the covers while the turret is standing still. It is the custom to mark the covers by means of die stamping but, owing to the fact that a rather sharp blow has to be used in order to mark the cover legibly and such sharp blow has a tendency to jar the machine as a whole as well as the cover feeding means, the tendency has been to diminish the impact, with the result that the covers are often illegibly or partially marked. In order to overcome this difficulty, both the cover feeding mechanism and the marking device supporting and operating means have been individually improved and have also been coordinated in a new manner as will presently appear.

The cover feeding means or device comprises the usual stack 25 for holding a supply of covers 26 and these covers are removed from the stack and fed forward by a reciprocatory feeding member 27. This member slides in guides 28 and receives its motion from a cam 29, mounted on shaft 30, with which cam engages a cam roll 31, carried by a slidable yoke 32, pivotally connected by means of a link 33 to an arm 34, carried by rockshaft 35. Rockshaft 35 carries an arm 36, pivotally connected by means of a link 37 to feeding member 27. Cam 29 is so formed that cover feeding member 27 is first given a forward movement sufficient to separate a cover from the stack and to feed it into position at the marking station of marking device 24. Said member 27 is then retracted slightly so as to free it from engagement with the cover that it has just fed to the marking station and, while said member 27 is so retracted, the punch of the marking device descends and strikes a sharp blow on the cover. Cover feeding member 27 now moves forward again so as to feed the cover from the marking station into pocket 8 of turret 7, and said member 27 is then retracted all the way back to put it in position to separate and feed the next cover. It will be seen that by this device the sharp impact which the punch of the marking device delivers to the cover will not be transmitted to cover feeding member 27 and will thus not tend to disarrange or jar the parts of the cover feeding device.

Marking device 24, although consisting of the usual anvil 38 and hammer or plunger 39, presents important features of improvement, as will presently appear. 40 indicates a bracket, having upper and lower jaws 41 and 42 that are spaced apart but connected (Figs. 3 and 6) so as to form a unitary structure, and this bracket 40 is secured to seaming mechanism housing 43 as by means of bolts 44. Housing 43 carries seaming mechanism 6 and its actuating means 45, and is slidably adjustable on framework 46 in a vertical direction by means of a suitable adjusting device conventionally shown and indicated at 47. It has been customary to have the seaming mechanism housing adjustable on the framework and to have the hammer of the marking device adjustable with it, but the anvil in such cases was then carried by the lower framework. The result of such

former construction was that a terrific jar was imparted to the elements associated with the lower part of the machine and a tremendous strain was exerted on the cam (such as 48) that actuated the hammer. In order to lessen the strain and jar it was customary to lessen the impact of the hammer as much as possible, with the result that the covers were often only partially, or illegibly, marked. Experience has shown that an impact of the order of fifteen tons to the square inch is necessary to adequately mark the stock of which the cover is made, and such pressure or blow can be made use of with the present construction without deleterious effects, as will now appear (Fig. 3). Cam 48 is carried by a sleeve 49 that is supported on bracket 50 bolted to housing 43. The motion of cam 48 is transmitted to hammer or plunger 39 by means of a bellcrank 51, pivoted at 52 on bracket 40, carrying at one end a cam roll 53 to engage cam 48 and having its other end pivotally connected at 54 to a link 55, which latter in turn is pivotally connected at 55a to toggle links 56 and 57. Toggle 56 is pivotally supported at 58 on bracket 40 and toggle 57 is pivotally connected at 59 to hammer or plunger 39. Bracket 40 is provided with a projection 60 carrying one or more freely rotatable abutment or thrust rollers 61 that engage beneath cam 48. It will be seen from the foregoing that sleeve 49 and therefore cam 48 is adjustable in unison with housing 53 and bracket 40. It will further be seen that, when cam 48 actuates plunger 39 and strikes the cover on anvil 38, the force of the blow is transmitted back through bracket 40 and in an upward direction to thrust roller 61 that bears against cam 48 and thereby tends to ease the strain on the same.

Turning now, for a moment, our attention back to the cover feeding means, it will be seen that stack 25, guides 28 and the other elements of said cover feeding means are carried by a supporting member or plate 62 slidably adjustable on rock-shaft 35 and connected to housing 43 at 63 and, therefore, adjustable with said housing. Adjacent the marking station are two cover supporting ledges 64 and 65 (Figs. 2, 4 and 6) that are supported by spring-pressed plungers 66 and 67 so that they will yield in a downward direction when the hammer strikes the cover. These spring-pressed plungers are seated in plate 62.

The means for actuating the machine are, in the present instance, as follows: Shaft 75 is the instrumentality from which motion is derived for operating the elements with which we are concerned. Shaft 75 has a clutch member 76 (Fig. 1) that engages a corresponding clutch member 77 on gear 78 fast on shaft 79. The clutch is interposed in the connections merely for the purpose of allowing the clutch members to disengage in case an obstruction to the running of the machine occurs. Gear 78 meshes with pinion 80 (Fig. 7) on shaft 81, which latter carries sprocket wheel 14 that drives chain 10 of the can-body conveyor. Shaft 79 also carries a gear 82 that meshes with and drives gear 83 on shaft 39, thereby operating both cams 48 and 29 and thus actuating the cover feeding means and the marking device. Shaft 79 further carries cam 2 that actuates the pedestal lifting means, and carries also a gear 84 that meshes with and drives gear 85 on shaft 18, the latter of which carries cam 17, whereby the turret is rotated. It is unnecessary to describe the operating means for the seaming mechanism.

The construction of the cover feeding device

and of the marking device and their interrelation are not claimed herein but form the subject matter of a divisional application filed October 6, 1943, Ser. No. 505,114.

5 I claim:

1. In a seaming machine having a seaming station at which a pedestal, having an opening in its surface, is located, and having an intermittently step-by-step rotatable turret provided with pockets to receive can-bodies, and in which each intermittent movement of said turret brings a pocket of said turret into position at said seaming station, the combination with said pedestal and said turret, of a can-body support, having an opening in its surface in line with the opening in said pedestal, extending in a straight line to said pedestal; an endless conveyor associated with said can-body support and said pedestal; a plurality of pins carried by said conveyor to project through the openings in the surfaces of said can-body support and said pedestal, each of said pins to advance a can-body over said support and uninterruptedly onto said pedestal at a uniform speed; means to move said conveyor at a uniform speed; a variable-speed mechanism and connections to actuate said turret, during each of its steps, first with an accelerated speed until the leading wing of that pocket which will be the next one to arrive at said seaming station has passed the next can-body that is being advanced on said support by said conveyor and a pin thereof; secondly with a speed substantially equal to that of said pin advancing said next can-body on said support until said can-body has been moved onto said pedestal by said pin at a uniform speed; thirdly with a slightly accelerated speed to thereby cause said pocket to engage said can-body, after the latter has been transferred to said pedestal, and to thereby free said can-body from said pin; and fourthly with a decelerating speed to center said can-body and bring it to a state of rest on said pedestal; and means and connections to elevate said pedestal after said can-body has been placed on said pedestal and while said can-body is being centered and brought to a state of rest on said pedestal, by said pocket.

2. In a seaming machine having a seaming station at which a pedestal, having an opening in its surface, is located, and having an intermittently step-by-step rotatable turret provided with pockets to receive can-bodies, and in which each intermittent movement of said turret brings a pocket of said turret into position at said seaming station, the combination with said pedestal and said turret, of a can-body support, having an opening in its surface in line with the opening in said pedestal, extending in a straight line to said pedestal; an endless conveyor associated with said can-body support and said pedestal; a plurality of pins carried by said conveyor to project through the openings in the surfaces of said can-body support and said pedestal, each of said pins to advance a can-body over said support and uninterruptedly onto said pedestal at a uniform speed; means to move said conveyor at a uniform speed; a cam and connections to actuate said turret, during each of its steps, first with an accelerated speed until the leading wing of that pocket which will be the next one to arrive at said seaming station has passed the next can-body that is being advanced on said support by said conveyor and a pin thereof; secondly with a speed substantially equal to that of said pin advancing said next can-body on said support

until said can-body has been moved onto said pedestal by said pin at a uniform speed; thirdly with a slightly accelerated speed to thereby cause said pocket to engage said can-body, after the latter has been transferred to said pedestal, and to thereby free said can-body from said pin: and fourthly with a decelerating speed to center said

can-body and bring it to a state of rest on said pedestal; and means and connections to elevate said pedestal after said can-body has been placed on said pedestal and while said can-body is being centered and brought to a state of rest on said pedestal, by said pocket.

WILLY DIEZEL.
